PORTABLE TAPE RECORDER

Bronislaw Zapolski, 145 Overlook Road,
Hastings on Hudson, N.Y.

Filed Dec. 15, 1959, Ser. No. 58,666

Term of patent 14 years

(Cl. D26—14)

T1 fig. 2.

Fig. 1 is a perspective view of a portable tape recorder embodying my new design and illustrates the front and right sides thereof and also illustrates the pivotal cover thereof in closed position;

Fig. 2 is a perspective view of same illustrating the rear and left sides thereof and the top cover in closed position;

Fig. 3 is a perspective view of the aforesaid tape recorder with the aforesaid cover removed thereby illustrating the escutcheon face of the tape recorder; and

Fig. 4 is a plane view looking down directly upon said escutcheon face.

The essential feature of my design is the escutcheon face including the truncated triangular cover overlying the magnetic heads and the tape guiding mechanism, the push button controls off-set to the left on the escutcheon face and the harmonizing knobs on the escutcheon face. The grill on the front side of the tape recorder is continuous within the border thereof.

I claim:

The ornamental design for a portable tape recorder, as shown and described.
